DESIGN FOR A COMBINED BAKING AND SERVING DISH OR SIMILAR ARTICLE

Edward A. Farr, Meriden, Conn., assignor to Manning, Bowman & Co., Meriden, Conn., a corporation of Delaware

Application August 24, 1935, Serial No. 58,272

Term of patent 7 years

To all whom it may concern:

Be it known that I, Edward A. Farr, a citizen of the United States, residing at Meriden, county of New Haven, State of Connecticut, have invented a new, original, and ornamental Design for a Combined Baking and Serving Dish or Similar Article, of which the following is a specification, reference being had to the accompanying drawing, forming a part thereof.

Fig. 1 is a perspective view of the dish showing my design;

Fig. 2 is a top plan view; and Fig. 3 is a side view thereof on a reduced scale. The embodiment of the invention shown comprises a stand or frame support having a pair of handle members, a bowl or lining part resting thereon, and a cover.

I claim:

The ornamental design for a combined baking and serving dish or similar article, substantially as shown and described.

EDWARD A. FARR.
